UNITED STATES PATENT OFFICE.

OTTO C. SCHWARZ, OF NEW CHICAGO, INDIANA.

DESIGN FOR A TOY CASTLE.

44,877.

Specification for Design.

Patented Nov. 11, 1913.

Application filed September 22, 1913. Serial No. 791,234. Term of patent 7 years.

To all whom it may concern:

Be it known that I, OTTO C. SCHWARZ, a citizen of the United States, and residing at New Chicago, in the county of Lake and State of Indiana, have invented a new, original, and ornamental Design for a Toy Castle, of which the following is a specification, reference being had to the accompanying drawing, forming a part thereof.

The figure of the drawing is a perspective view of a toy castle embodying my novel design.

I claim—

The ornamental design for a toy castle, as shown.

OTTO C. SCHWARZ.

Witnesses:

G. E. DOWLE,

W. L. HALL.
